J. W. McCRONE

REFRIGERATOR.

APPLICATION FILED JUNE 1, 1920.

1,387,159.

Patented Aug. 9, 1921.

Inventor
J. W. McCrone.

UNITED STATES PATENT OFFICE.

JOHN WALKER McCRONE, OF KANSAS CITY, MISSOURI.

REFRIGERATOR.

1,387,159.

Specification of Letters Patent. Patented Aug. 9, 1921.

Application filed June 1, 1920. Serial No. 385,663.

To all whom it may concern:

Be it known that I, JOHN WALKER McCRONE, a citizen of the United States, residing at Kansas City, in the county of Jackson, 5 son and State of Missouri, have invented certain new and useful Improvements in Refrigerators, of which the following is a specification containing a full, clear, and exact description, reference being had to the 10 accompanying drawings, forming a part hereof.

My invention relates to improvement in the means and method used in reducing the temperature of refrigerators, by the use of 15 salt and ice containers or brine containers connected with a source of refrigeration.

The objects of my invention are, first, to provide metallic tanks or containers, constructed to carry a quantity of broken ice 20 and salt, or brine connected with a source of refrigeration, and having a plurality of vertical flanges extending laterally from the sides thereof, for the purpose of increasing the metallic surfaces of the containers or 25 tanks exposed to the air to be cooled.

Second: To provide a means to convey salt water or brine from the inside of the tanks or containers to the outside and to the flanges attached thereto, for the purpose of 30 removing frost and ice and to prevent the accumulation of frost and ice upon the outside of the tanks and the vertical flanges attached thereto.

Third: To provide a means for replenishing the salt and ice containers, or brine containers with a source of refrigeration, or 35 refrigerating material.

Fourth: To provide the containers with a means of drainage.

Fifth: To provide a means of increasing or diminishing the refrigerating surface exposed to the air content of the refrigerator.

Sixth: To provide a means of refrigeration adaptable to many, or all styles, designs 45 or plans of refrigerators.

Figure 1 is a perspective elevation of my improvement. Fig. 2 is a perspective detail of a tank or container, and a coil of pipe from a source of refrigeration, the vertical laterally extending flanges attached to the sides of the containers, or tanks and the disposition of the material used to convey salt water or brine from the inside to the outside of the tanks and vertical flanges. 50

Similar letters refer to similar parts throughout the drawings.

Referring by letters to accompanying drawings,

The letters "I" refer to salt and ice, or brine containers or tanks. 60

The letter "C" refers to vertical flanges of sheet metal laterally extending from the sides of "I", Figs. 1 and 2, into air spaces or ducts B, formed by spacing apart the tanks "I" from each other, and secured in 65 that position by the front and rear end plates "A".

The letter "D" refers to sheets of fibrous or textile material disposed along the inside sides of tank "I" from end to end and from 70 the bottom of tank "I" to the top edge of the side of the tank "I" and over the top and down on the outside to the flanges "C" for the purpose of conveying salt water or brine to the outside surfaces of the tanks 75 "I" and the vertical flanges "C" attached thereto, to prevent and remove frost and ice therefrom.

The letter "E" refers to pipes connecting the tanks "I". 80

The letter "G" refers to a three-way cock for the purpose of draining tanks "I" of a section consisting of a plurality of tanks "I" spaced apart and secured in position by front and rear plate "A". 85

The letter "H" refers to a pipe Fig. 2, introduced into a tank "I" or a series of tanks forming a section when the same are to be filled with brine instead of salt and ice, and connected with a source of refrigeration. 90

The letter "J" refers to a frame or rack constructed to carry a plurality of tank sections, one above another and arranged so that the vertical air ducts "B" will register 95 to form a continuous flue.

The letter "K" refers to the horizontal air spaces between the sections.

The letter "L" refers to the arrows representing the course of the current of warm 100 air to the refrigerating tanks.

The letter "M" refers to arrows representing the course of the currents of cooled air away from the tanks.

The letters "O" and "P" represent the flow 105 from a source of refrigeration.

The letter "R" refers to the runs or slides on which the sections of tanks rest when placed in the rack or frame "J". The manner or method of using this means of refrigeration is to fill the tanks of each section with ice and salt. The frame "J" hav- 110

ing been placed in the ice compartment of a refrigerator, the sections are placed on their respective slides and the door to the ice compartment closed. The ice and salt 5 mixture produces a very low temperature at the tanks. The warm air "L" is cooled and settles to the bottom of the ice compartment. This action of the air produces a circulation of air, which extends to all parts of a refrigerator connected with the ice compartment. The intense cold produced in the tanks "I" causes moisture to condense and form ice 10 and frost on the outside of the tanks "I" and the vertical flanges "C"; the salt water 15 formed by the ice and salt is conveyed to the outside surfaces of "I" and the flanges "C", and melts the ice and frost, also prevents it forming. When the tanks "I", need reicing, the water is drawn off by the drain 20 cock, G, the top salt and ice container, or tank, is withdrawn wholly or the greater part of the way from its place in the frame, or rack, J, and is filled with salt and ice, and replaced. As many sections may be 25 charged with ice and salt as appears necessary and when a means of refrigeration, such as brine circulating from an ice machine or other source of refrigeration, the coils are introduced into the tanks "I", 30 which are filled with brine which is reduced to a very low temperature. The salt water conveying material "D" furnishes brine to the outside of the tanks. The frost is kept off and the combination much more efficient 35 than the coil alone.

Having thus described my invention, what I claim as new therein and desire to secure by Letters Patent of the United States is:

1. In a refrigerator a salt and ice container, consisting of a plurality of rectangular shaped tanks, spaced apart from each other and connected at their ends, in such a 40

manner as to make up a section having ice and salt tanks alternately with vertical air spaces between them; vertical wings or flanges extending from the sides of the ice and salt containers, sheets of fibrous or textile material disposed on the inner and outer surfaces of the salt and ice containers, whereby salt water is conveyed from the inside to the outside of the containers, and the vertical wings or flanges, for the purpose of preventing or removing frost and ice thereon. 45

2. The combination of a plurality of salt and ice tanks or containers spaced apart from each other, a plurality of vertical air spaces formed by such spacing apart, a plurality of vertical wings or flanges extending laterally from the sides of the containers into the vertical air spaces between them, sheets of fibrous or textile material, disposed on the inner and outer surfaces of the salt and ice containers, for the purpose of conveying salt water to the outside of the containers, and to the flanges attached to the containers, for the purpose of removing frost and ice therefrom, a plurality of pipes connecting tanks, cocks for the purpose of drainage, with a frame work, so arranged that several containers, may be placed one above another, in such a manner that the vertical air flues caused by the several ice tanks being spaced apart laterally from each other, will register and form a continuous 60 vertical air flue. 65

In testimony whereof I have signed my name to this specification in the presence of two subscribing witnesses.

JOHN WALKER McCRONE.

Witnesses:

ELIZABETH GARNIER,
JOSEPH M. GORMAN.
